UNITED STATES PATENT OFFICE.

BENJAMIN F. BETTS, OF TONAWANDA, NEW YORK.

IMPROVED MACHINE FOR CUTTING THIN LUMBER.

Specification forming part of Letters Patent No. 39,113, dated July 7, 1863.

To all whom it may concern:

Be it known that I, BENJ. F. BETTS, of Tonawanda, county of Erie, State of New York, have invented a new and useful Improvement in Machines for Cutting Thin Lumber; and I do hereby declare that the following is a full, clear, and exact description of the construction and operation of the same, reference being had to the annexed drawings, making a part of this specification, of which—

Figure 1 is a plan with movable bed-plate in position; Fig. 2, likewise a plan with said bed-plate removed for the purpose of showing the arrangement beneath for elevating or depressing it, and Fig. 3 a side elevation of screw and eccentrics.

B is the box within which the block of wood to be cut is placed; b, the rods or guides upon which said box slides; A, movable bed-plate; c, knife attached to the immovable bed-plate D; m, the eccentrics upon which the movable bed-plate A rests.

The block of wood to be cut is placed within the box B, its own weight causing it to rest upon the bed-plate A. The box is then moved forward upon the oblique guides b, carrying the block forward and laterally (corresponding to the motion of the box B) over the knife c, thereby shaving off from the under side of the block a board equal in thickness to the

height of the edge of the knife c above the bed-plate A. The knife c, being set diagonally to the box B, lessens the tendency to check the lumber.

The machine is gaged for cutting different thicknesses by causing the eccentrics m (upon which the bed-plate A rests) to rotate conjointly, thereby elevating or depressing the bed-plate, thus increasing or diminishing the vertical distance between the bed-plate A and the knife c.

I do not claim the principles involved in this machine; but

I do claim the combination and arrangement of those as herein described, viz :

The sliding box with oblique motion, thereby giving by movement of the block a drawing cut to the knife, in combination with the diagonal position of the knife attached to the immovable bed-plate, and the arrangement of eccentrics for elevating or depressing the movable bed-plate. The bed-plates here referred to are plane surfaces, and when plate A is raised to a level with edge of knife, both bed-plates and upper side of knife form one plane surface.

BENJ. F. BETTS.
